APPARATUS FOR DISPENSING LIQUIDS

John Fraser, Tolworth, Surbiton, England, assignor to Avery-Hardoll Limited, Tolworth, Surbiton, England.

Application December 11, 1951, Serial No. 261,069.

Claims priority, application Great Britain December 14, 1950

7 Claims. (Cl. 226—125)

1

This invention relates to apparatus for dispensing liquids, the apparatus being intended primarily for the dispensing of lubricating oil to vehicles at garages and like establishments. It has been the usual practice of some manufacturers of lubricating oils to supply the oil in sealed containers of various sizes, which are opened only when the lubricating oil is supplied to a customer by a garage, but otherwise oil has commonly been dispensed from a bulk supply, jug-like measures being used in which the oil was carried from the supply to the vehicle for which it was intended. The use of sealed containers is restricted by the availability of the containers, and the supply in measures is both open to abuse by inaccurate filling of the measures, and unsatisfactory from the point of view of cleanliness, since the measures, being always coated with oil, readily retain dust and other foreign matter. Wet hose dispensing systems have been proposed, but are necessarily expensive, and in view of the relatively small total sales of lubricating oil by normal garages, and the number of different brands and grades which must be stocked, they are not an economic proposition except for very large establishments.

An object of the invention is to provide a liquid dispensing unit which defeats any attempt by the user to give short measure or to mix a liquid called for with an inferior grade. Another object is to provide a liquid dispensing apparatus including such a unit, the apparatus as a whole being arranged to supply the liquid in a clean and uncontaminated condition.

A further object is to provide a dispensing apparatus which can be used selectively for supplying any one of a number of oils or other liquids, and enables the purchaser to ascertain that the correct liquid is supplied.

According to one feature of the invention, a liquid dispensing unit comprises a cylinder, a piston displaceable in one direction by liquid entering the cylinder through an orifice and movable in the other direction to expel the said liquid through the same orifice, a valve in said orifice having manual opening and closing means, and means for preventing the closing of the valve except when the cylinder is either completely full or completely empty.

The piston is preferably spring-urged in a direction to empty the cylinder. The means for preventing closing of the valve may comprise radially movable members held in their closure preventing position by a sleeve moving with the piston, and the said radially movable members

2

are preferably moved positively to their valve closure preventing position by movement of the piston from either of its extreme positions.

According to another feature of the invention, apparatus for dispensing liquids comprises, in combination, a dispensing unit according to either of the preceding paragraphs, a supply point, and means for connecting said supply point to a source of liquid under pressure, the supply point being provided with a valve co-operating with the valve in the dispensing unit, and the dispensing unit and supply point being provided with interlocking means, the engagement of which brings the valves to a position in which the valve of the dispensing unit, when opened, imparts opening movement to the valve in the supply point, the opening of the valves preventing release of the interlocking means.

A plurality of supply points are preferably provided in a single supply unit.

The invention is hereinafter described with reference to the accompanying drawings, in which—

Figure 1 is a sectional elevation of a complete liquid dispensing apparatus according to the invention for dispensing lubricating oil to motor vehicles;

Figure 2 is an elevation, partly in section, of a liquid dispensing unit, the piston being shown in the position which it occupies when the unit is empty;

Figure 3 is a section on the line 3—3 of Figure 2, but showing the piston in the position which it takes up when the unit is full;

Figure 4 is a detail view, in elevation, of the nozzle end of the dispensing unit;

Figure 5 is a section through one of the supply points of the dispensing apparatus showing the nozzle of the dispensing unit inserted therein but not interengaged therewith to prevent withdrawal;

Figure 6 is a view similar to Figure 5 but showing the dispensing unit interengaged with the supply unit, and the valves open;

Figure 7 is a plan view of a supply point, partly in section on the line 7—7 of Figure 5, and

Figure 8 is a section on the line 8—8 of Figure 5.

Referring to Figure 1 of the drawings, a supply unit 10 comprises a hollow pedestal having a base 11, inner and outer tubular walls 12 and 13, and a fixed annular top plate 14 extending between the walls 12 and 13. Mounted in the plate 14, in circumferential array, are a number of supply points 15 which are equally angularly

spaced except that twice the normal spacing is provided between one pair of adjacent points. Each supply point 15 is connected by a conduit 16 to a supply of oil under pressure, the conduits 16 being led out through the base of the pedestal. A cover plate 17 is rotatably mounted at 18 on the plate 14, the cover plate 17 having a frusto-conical edge surface 19 which is surrounded by a rim 20 secured to the plate 14, the rim 20 being formed with windows 21. A single hole 22, on the same pitch circle as the supply points 15 is provided in the cover plate 17, and legends are printed or otherwise marked on the surface 19 so that when the hole 22 registers with any supply point, a legend is visible in each window indicating the brand and grade of oil available at that supply point.

The space within the upper portion of the inner tubular wall 12 provides a housing for a dispensing unit 23 when the latter is not in use, the unit 23 resting on a rubber ring 24 supported on a flange 25. A cap 26, hinged at 27 on the cover plate 17, covers, when closed, the housing for the dispensing unit 23 and the hole 22, being secured in the closed position by the hooked end of one arm 28 of a latch member pivotally mounted at 29 on the cover plate 17. The latch member has a second arm 30 which, when the latch is operative, enters, if the cover plate is in the correct angular position, between two lugs 31 on the plate 14, thus preventing rotation of the cover plate 17. The latch member is urged by a spring 32 to the engaged position, and is retained in that position by a key-operated lock 33.

Referring now to Figures 2, 3 and 4 of the drawings, the dispensing unit 23 comprises a transparent cylinder 34 located in an apertured metal casing 35 integral with a frusto-conical end member 36 tapering to a delivery nozzle 37. A second end member 38 is screwed into the other end of the casing 35, the end member 38 having attached to it a laterally projecting handle 39. A piston 40 having a short cylindrical portion 41 which fits in the cylinder 34 and carries a liquid-tight packing ring 42, has a tapered portion 43 the cone angle of which is very slightly larger than that of the end member 36, terminating in a short cylindrical portion 44. The nozzle end of the member 36 is divergent outwardly, the delivery nozzle 37 being a separate member which is a press fit on an externally cylindrical part of the member 36, the bore of the nozzle being divergent outwardly as shown at 45, and having a pair of diametrically opposed longitudinal grooves 46 in its inner wall.

A tubular stem 47 projects into the cylinder 34 from the end member 38, and slides within a sleeve 48 fixed to the piston 40. A valve rod 49 extends through the stem 47 and sleeve 48, passing through a bore 50, in which is fitted a packing ring 51, in the piston 40. The valve rod 49 carries, at one end, a valve member 52 having two frusto-conical portions with different angles of conicity, fitting respectively in the divergent end of the member 36 and in the nozzle 37, the latter portion being slotted diametrically to receive a plate 53, secured by rivets 54, the ends of the plate 53 constituting radial wings 55 co-operating with the grooves 46 in the nozzle to prevent rotation of the valve member. The valve member 52 is urged towards its closed position by a spring 56 surrounding the valve rod 49, and is opened by a trigger lever 57 pivotally attached to the handle 39 and housed in a recess 58 in the said handle.

The piston 40 is urged towards the nozzle end of the unit by a spring 59. The sleeve 48 is enlarged internally at its ends, as shown at 60 and 61, chamfered rings 62 and 63 being fitted against the shoulders formed by the changes of bore diameter. The stem 47 is formed with three apertures 64 in a common plane perpendicular to its axis, to locate three balls 65, the spacing of the rings 62 and 63 being such that when the piston is at the nozzle end of the unit, as shown in Figure 2, the balls can move out into the enlargement 60, whilst when the piston is at the other end of its stroke, the balls can move out into the recess 61, movement of the piston away from either of these positions causing the balls to be forced radially inwardly into the stem 47. A chamfered disc 66 is mounted on the valve rod 49, and the balls 65, when in their inward position, act between the edges of the holes 64 and the surface of the disc 66 to hold the valve member 52 in the open position, the chamfer on the rings 62 and 63 being so arranged that movement of the piston forces the balls inwardly and thus ensures that such movement is accompanied by opening of the valve member to a substantial extent. A light coil spring 67 is mounted inside the stem 47, and, when the balls 65 are in their inward positions, this spring acts on them at points radially outwardly of their centres, thus tending to hold them in the position in which they hold the valve member open. A plunger 68, having a conical nose 69, is mounted on the valve rod 49, having a limited lost motion thereon and being urged towards the valve member 52 by a spring 70, the nose 69, when the valve rod 49 is moved to open the valve fully, engaging the balls to displace them outwardly against the resistance of the spring 67.

The nozzle 37 is provided with a pair of wings 71 which engage, as hereinafter described, with a groove in the supply unit to hold the dispensing unit in position therein, these wings being chamfered as shown at 72 in Figure 4, to provide easy engagement with the said groove.

Referring now to Figures 5 to 8, each supply point 15 includes a tubular body 73 located in an opening in the plate 14, to which the body is secured by bolts, one of which is shown at 74, passing upwardly through a flange 75 on the body 73 into tapped holes in the plate 14. The upper end of the body 73 is shaped internally at 76 to receive the nozzle 37 of the dispensing unit, and is formed with an internal groove 77, the upper wall of which is cut away at 78, to receive the wings 71 on the nozzle, a stop 79 (Figure 7) being provided in the groove which co-operates with one of the wings 71 to limit angular movement of the nozzle when it is inserted in the body 73. A movable valve seat member 80 is mounted in an enlarged cylindrical part of the body 73 below the part 76, the valve seat member having depending legs 81 one of which is slotted longitudinally at 82 to receive a set screw 83 which prevents the seat member 80 from rotating whilst allowing it to move axially. A packing ring 84 prevents leakage of oil between the seat member 80 and the body 73. The seat member 80 is urged upwardly by a spring 85 against a shoulder 86 in the body, the spring 85 taking its abutment on a disc 87 supported by legs 88 from a plug 89 screwed into the lower end of the body at 90. The seat member has an upwardly convergent frusto-conical bore into which a valve member 91 having a frusto-conical land 92 is urged by a spring 93, the valve member having a

flange 94 which lies between the legs 84 and serves to guide the valve member; the flange 94 also seating on a lip 80a on the seat member 80 to close the passage through the seat member. At the upper end of the frusto-conical bore in the seat member 80 there is formed an inwardly projecting rib 95 (Figure 8), which is grooved at two diametrically opposite points, at 96. These grooves are so positioned that they are aligned with the wings 55 on the valve member 52 of the dispensing unit when the wings 71 of the said unit have been entered into the groove 77 and the dispensing unit turned to bring one of the said wings 71 up against the stop 79.

The plug 89 has a through bore 97 which is reduced in diameter at its upper end to receive a plunger 98 notched at 99 and having a flange 100 at its upper end which rests normally on the top of the plug 89. The plunger 98 has a small passage 101 passing through it. Any substantial flow of oil from the conduit 16 through the supply unit 15 lifts the plunger 98; and, in doing so, rocks a lever 102 to the position shown in Figure 6, the lever being connected to an external indicator (not shown), which thus indicates when oil is flowing.

When the dispensing unit 23 is empty, the piston 40 is at the nozzle end of the unit as shown in Figure 2, and there is substantially no residue of oil left therein. To fill the dispensing unit, the nozzle 37 is inserted into a supply unit 15, the wings 71 being passed through the notches 73, and the dispensing unit turned through 90° to engage the wings 71 in the groove 77, and bring one wing 71 up against the stop 79. The wings 55 on the valve member 52 are then in alignment with the grooves 96 in the valve seat member, and the rim of the nozzle 37 makes a fluid-tight joint with the seat member 80, forcing the latter slightly away from the shoulder 86 against the spring 85.

Operation of the trigger lever 57 will then open both the valve member 52 in the dispensing unit and the valve member 91 in the supply unit, such action being impossible in any other relative angular position of the two units, as the wings 55 are obstructed by the valve seat member 80, and the valve member 52 cannot displace the valve member 91 relative to its seat. As soon as oil starts to flow through the valves into the dispensing unit, the balls 65 are pushed inwardly by the sleeve 48 to a position in which they act on the disc 66 to prevent upward movement of the valve rod, and the valves are therefore prevented from closing until the dispensing unit is full, the piston 40 having reached the position shown in Figure 3, in which the balls can move outwardly into the recess 64, and allow the valves to close. It will be noted that whilst the valves are open, the dispensing unit cannot be removed from the supply unit, since the wings 55, being in engagement with both the grooves 46 in the nozzle 37, and the grooves 96 in the seat member 80, prevent relative turning of the two units. The dispensing unit therefore cannot be removed from the supply unit until it is full, thus ensuring that it is completely filled.

The filled dispensing unit is then removed from the supply unit, and its nozzle inserted into, for example, the oil filling orifice of a vehicle engine, the valve member 37 being kept in the closed position meanwhile. The valve member 37 is then opened by operating the trigger lever 57, and oil commences to flow from the dispensing unit, being forced out by the spring 59. The

initial movement of the piston causes the chamfered ring 63 to act on the balls 65 and urge them inwardly, and they are retained in their inward position by the sleeve 48 until the dispensing unit is empty. Thus commencement of delivery of the oil is necessarily accompanied by movement of the balls to the position in which they hold the valve open, and it is impossible to stop the delivery before the whole contents of the dispensing unit has been delivered, although the valve member 52 may be moved within limits to vary the rate of delivery. When the dispensing unit is completely empty, the balls 65 are opposite to the recess 60 in the sleeve 48, but the spring 67 prevents them from moving outwardly, and manipulation of the trigger lever 57 to bring the frusto-conical nose 69 of the plunger 68 between the balls is necessary to displace them outwardly. Such manipulation of the trigger lever opens the valve to its widest extent, giving free escape for the last drops of oil in the dispensing unit.

Similar full opening of the valve member 52 must be effected to produce displacement of the balls 65 when the dispensing unit has been filled. Thus the valve member 52 must always be opened fully at the end of a filling or emptying operation, giving the freest possible flow of oil into or out of the dispensing unit, and even if the chamfered rings 62 and 63 are so positioned that the balls 65 cease to be retained in their inward position by the sleeve 48 slightly before the piston reaches the end of its stroke, the valve must be so far open to allow their outward movement that the piston stroke will be completed before the valve closes.

Any one of the supply points 15 may be made accessible to the dispensing unit 23 by rotating the cover plate 17 to a suitable position, and the appropriate legends on the edge 19 of the plate 17 are visible through the windows 21 when the plate is rotated to the desired position. Access to the dispensing unit 23 in its housing is obtained by lifting the cap 26, which opens against a resilient stop 103 (Figure 1). The hole 22 in the cover plate 17 is arranged to register with the gap between supply points 15 when the said plate is locked against rotation, so that all the supply points are covered and protected from dust and other foreign matter.

Dispensing units of different sizes may be provided for supplying different quantities of oil, in order to avoid filling a small unit several times when a large quantity is required.

Whilst the above particular description relates to dispensing apparatus for oil, and the dispensing of oil is believed to be the primary field of usefulness of the invention, it is to be understood that apparatus according to the invention may also be used in the dispensing of other liquids.

I claim:

1. A liquid dispensing unit comprising a cylinder, a piston mounted in said cylinder and movable between two terminal positions therein, means acting on the piston to urge it towards one terminal position at one end of the cylinder, a valve to close an orifice in the said end of the cylinder, resilient means acting on said valve to close it, manual opening means connected to said valve, means to hold said valve in the open position and means carried by the piston to hold the valve holding means in its operative position at all positions of the piston intermediate its terminal positions.

2. A liquid dispensing unit comprising a cyl-

inder, a piston mounted in said cylinder and movable between two terminal positions therein, means acting on the piston to urge it towards one terminal position at one end of the cylinder, a valve to close an orifice in the said end of the cylinder, resilient means acting on the said valve to close it, a stem fixed to said valve, means to move said stem axially to open the valve, a collar on said stem, a tube fixed in said cylinder and surrounding said stem and collar, a radial aperture in said tube, a detent member located in said aperture and movable into the path of said collar when the valve is open to prevent closing of the said valve, and a sleeve carried by the piston and surrounding said tube, the sleeve having formed on it a cam surface to displace the detent member into the path of the collar as the piston moves from either of its terminal positions and retain the detent member in the path of the said collar until the piston reaches its other terminal position.

3. A liquid dispensing unit comprising a cylinder, a piston mounted in said cylinder and movable between two terminal positions therein, resilient means acting on the piston to urge it towards one terminal position at one end of the cylinder, a valve to close an orifice in the said end of the cylinder, a tube fixed to said cylinder and extending inwardly from the other end thereof, a stem fixed to said valve and passing through said tube, manual means to move said stem axially to open said valve, a collar on said stem, a detent member located in a radial aperture in said tube, cam means mounted on said piston and having a cam surface to displace the detent member into the path of the collar as the piston moves from either of its terminal positions and retain the said detent member in the path of the said collar until the piston reaches its other terminal position, resilient holding means to hold said detent member in the path of said collar independently of the cam means, and a release member carried by the stem to move the detent member out of the path of the collar against the resistance of said resilient holding means.

4. A liquid dispensing unit comprising a cylinder, a frusto-conical extension at one end of the said cylinder, a handle at the other end of said cylinder, a piston in said cylinder movable between two terminal positions therein, a frusto-conical extension on said piston which enters and substantially fills the frusto-conical extension of the cylinder at one terminal position of the piston, a nozzle at the apical end of said cylinder extension formed with an outwardly divergent orifice, a frusto-conical valve member to close said orifice, a rod fixed to said valve member and extending through said piston to the other end of the cylinder, a trigger lever pivotally mounted on said handle and engaging said rod to apply a thrust thereto to open the valve, a tube in said cylinder fixed to the handle end thereof and surrounding the rod, a sleeve fixed to the piston and surrounding the tube, a coiled compression spring surrounding the sleeve, abutments for said spring on said cylinder and piston whereby the said spring acts to urge the piston towards the nozzle end of the cylinder, spring means acting on said rod to close said valve member, a detent member located in a radial hole in said tube, a collar on said rod, the interior of said sleeve having a central portion of uniform diameter and end portions of larger diameter, each of the said larger diameter portions co-operating with the detent member when the piston is in one of its terminal

positions to allow the detent member to assume an outward position, and the central portion of said sleeve co-operating with the detent member at all times when the piston is between its terminal positions to displace the detent member inwardly, the detent member in its inward position engaging the collar to prevent closing of the valve member.

5. In liquid dispensing apparatus, the combination of a liquid dispensing unit and a supply unit for filling the said dispensing unit, said dispensing unit and supply unit having mutually engaging interlocking means, the liquid dispensing unit comprising a cylinder, a piston mounted in said cylinder and movable between two terminal positions therein, means acting on the piston to urge it towards one terminal position at one end of the cylinder, a valve to close an orifice in the said end of the cylinder, resilient means acting on said valve to close it, manual valve opening means, means to hold said valve in the open position, and means carried by the piston to hold the valve holding means in its operative position at all positions of the piston intermediate its terminal positions, and the said supply unit comprising a source of liquid under pressure, a socket, conduit means connecting said socket to said source, and valve means in said socket, adapted for opening by movement of the valve in the dispensing unit to the open position and interengaging elements on the valve in the dispensing unit and in said socket, said interengaging elements co-operating when the dispensing unit is interlocked with the supply unit to prevent disengagement of the interlocking means.

6. In liquid dispensing apparatus, the combination of a liquid dispensing unit and a supply unit for filling the said dispensing unit, the liquid dispensing unit comprising a cylinder, a piston mounted in said cylinder and movable between two terminal positions therein, means acting on the piston to urge it towards one terminal position at one end of the cylinder, a valve to close an orifice in the said end of the cylinder and movable outwardly in said orifice to its open position, radial wings on said valve engaging grooves in the wall of said orifice, resilient means acting on said valve to close it, manual valve opening means, means to hold said valve in the open position, and means carried by the piston to hold the valve holding means in its operative position at all positions of the piston intermediate its terminal positions, and said supply unit comprising a source of liquid under pressure, a socket, conduit means connecting said socket to said source, valve means in said socket engaged by the valve in the dispensing unit for opening thereby, and means co-operating with the wings on the valve in the dispensing unit to permit opening of the valves in only one relative angular position of the dispensing unit and socket, mutually engaging interlocking means being provided on said dispensing unit and in said socket and said wings and co-operating means being positioned to allow opening of the valves when said interlocking means are engaged.

7. In liquid dispensing apparatus, the combination of a liquid dispensing unit and a supply unit for filling the said dispensing unit, the liquid dispensing unit comprising a cylinder, a piston mounted in said cylinder and movable between two terminal positions therein, means acting on the piston to urge it towards one terminal position at one end of the cylinder, a nozzle at that

end of the cylinder, a valve to close an orifice in the said nozzle and manual valve opening means, and the supply unit comprising a plurality of sources of liquid under pressure, a plurality of sockets each connected to one of said sources and each adapted to receive said nozzle, means to retain said nozzle in each of said sockets, valve means in each of said sockets adapted for opening by movement of the valve in said nozzle to the open position, a shield having a single opening therein and movable to align said opening with any one of the sockets, and indicating means associated with the shield to provide an indication changing with the position of the shield.
